[57] CLAIM

The ornamental design for a combined planter unit and bracket, as shown and described.

DESCRIPTION

FIG. 1 is a perspective view of a combined planter unit and bracket embodying our new design;

FIG. 2 is an enlarged front elevational view thereof;

FIG. 3 is an enlarged bottom plan view thereof;

FIG. 4 is an enlarged rear elevational view thereof;

FIG. 5 is an enlarged right side elevational view thereof, the left side being a mirror image thereof;

FIG. 6 is an enlarged bottom plan view of the plant receptacle shown separately for ease of illustration;

FIG. 7 is an enlarged bottom plan view of the planter unit shown separately for ease of illustration.
